UNITED STATES PATENT OFFICE.

ISAAC S. CRAIG, OF SOMERVILLE, ASSIGNOR TO THE STANDARD RIVET COMPANY, OF BOSTON, MASSACHUSETTS.

STOP-MOTION FOR MACHINES.

SPECIFICATION forming part of Letters Patent No. 448,578, dated March 17, 1891.

Application filed April 16, 1890. Serial No. 348,140. (No model.)

To all whom it may concern:

Be it known that I, ISAAC S. CRAIG, of Somerville, in the county of Middlesex and State of Massachusetts, have invented a new and useful Stop-Motion for Machines, of which the following is a specification, reference being had to the accompanying drawings, in which—

Figure 1 is a plan of my new stop-motion as it appears when applied to a rivet-setting machine, the standard of the latter being sectioned. Fig. 2 is an enlarged sectional elevation on line 2 2 of Fig. 1; and Fig. 3 a similar elevation, but showing the parts in positions different from those they occupy in Fig. 2.

The object of my invention is to produce a stop-motion for driving and other machines, whereby the driver, for example, is rendered alternately operative and inoperative to drive the fastening (to give the operator time to feed his work.)

In the drawings, in which I show my new coupling applied to the main shaft of a rivet-setting machine, although it may be used in a great variety of other machines, A is the frame; a, the main shaft; a', an eccentric fast on main shaft a; a², the eccentric-strap, and a³ the rod connecting the main shaft to the head of the machine, in this case to a driver-bar, which, however, is not shown, because the connection will be readily understood by all skilled in the art.

B is the driving-pulley loosely mounted on main shaft a, and is formed with a flange b, the edge of which is a cam-surface (see Fig. 1) having a projection b'. (See Figs. 2 and 3.)

D is a sleeve fast on main shaft a, and d' is a forked lever fulcrumed to sleeve D at d². Lever d' is formed with projections d³, d⁴, and d⁵, a spring d⁶ (in this case mounted in a socket in sleeve D) engaging projection d³ to throw the projection d⁴ into engagement with projection b', as hereinafter explained.

F is a lever fulcrumed at f and connected to the rocker-arm (or its equivalent) F' by a detent f', the detent being fulcrumed on arm f² of rocker-arm F', and having a recess f³ to engage projection f⁴ on lever F. A spring f⁵ co-operates with spring f⁶ to keep

the projection f⁴ normally in the socket f³ of the detent, which has a lip f⁷ to prevent the spring f⁸, by means of which the treadle F² is sustained in its highest position, Fig. 3, from pulling detent out of engagement with the projection f⁴. It is desirable to provide a stop f⁹ to prevent the free end of lever F from riding on the flange b of the pulley.

The operation of my coupling is as follows: When the parts are in the position shown in Fig. 3, the projection d⁴ on forked lever d' is in engagement with the projection f¹⁰ on the free end of lever F, and held in this position against the force of spring d⁶, as shown in Fig. 3. When the treadle is depressed, as shown in Fig. 2, the detent f' pushes lever F out of engagement with projection d⁴, and this projection is snapped into engagement with the cam-surface on flange b by the spring d⁶. Rotation of pulley B brings the projection b' into engagement with the projection d⁴, and the pulley is thus coupled to its shaft a. As the pulley rotates, the projection d⁵ is brought into engagement with the free end f¹¹ of the detent f' and the detent f' is moved out of engagement with the projection f⁴, and the lever F, under the tension of spring f⁵, moves toward the shaft a into the path of the projection d⁴. Further rotation brings projection d⁴ into engagement with the side of the free end f¹² of lever F, which is best curved slightly, as shown in Fig. 1, thereby moving the projection d⁴ out of the path of the notched flange b and allowing the pulley to run free, the projection d⁴ bringing up against projection f¹⁰, as shown in Figs. 1 and 3. When the treadle is depressed, the shaft and pulley are coupled. The lever F is brought into position to move projection d⁴ out of engagement with the flange as soon as the projection d⁵ has tripped the detent by engagement with the free end f¹¹, the shaft and pulley remaining coupled, however, until the projection d⁴ is brought into engagement with the free end f¹² of lever F. Each time the driving-rod a³ is raised to actuate the treadle-driver the driving pulley and shaft are coupled and remain coupled until the projection d⁴ engages free end f¹² of lever F. A second fastening

cannot be driven until the treadle returns to its position of rest and is again depressed.

In rivet-setting machines it has frequently happened that an operator has driven a fastening on top of one already set, owing to the rapid movement of the machine and the operator's slowness in moving his work. By the use of my new stop-motion or coupling the machine is rendered inoperative as soon as one fastening is driven, and remains inoperative until the lever F is again moved out of the path of the projection d¹, through treadle F², detent f', and projection d⁴.

My new stop-motion is shown attached to the machine shown in Frank Bean's application, Serial No. 348,257, filed April 16, 1890, of even date herewith.

What I claim as my invention is—
In a setting-machine, the combination of

shaft a, loose pulley B, eccentric a', its strap a² and rod a³, with rocking lever d', rotating with shaft a, lever F, and rocking detent f', pulley B being provided with a cam b and projection b', lever d' with projections d⁴ d⁵, lever F with a cam-surface f¹² and shoulder f¹⁰, projection d¹, engaging projection b' to couple the pulley and shaft, projection d⁵, engaging lever f' to bring cam-surface f¹² and shoulder f¹⁰ into the path of rocking lever d⁴, and cam-surface f¹², rocking lever d⁴ out of engagement with b' to allow pulley B to run free, and shoulder f¹⁰, arresting lever d⁴, all substantially as and for the purpose set forth.

ISAAC S. CRAIG.
